[57] **CLAIM**

The ornamental design for a thermoregulator, as shown and described.

DESCRIPTION

FIG. 1 is a front elevational view of a thermoregulator housing and stand for same showing my new design; FIG. 2 is a left side elevational view thereof, the right side being substantially a mirror image thereto; FIG. 3 is a rear elevational view thereof; and FIG. 4 is a top plan view thereof.

FIG. 4
